UNITED STATES PATENT OFFICE.

PAP YONOS, OF CANTON, OHIO.

CAR-DOOR LOCK.

1,232,157.

Specification of Letters Patent.

Patented July 3, 1917.

Application filed April 26, 1917. Serial No. 164,646.

To all whom it may concern:

Be it known that I, PAP YONOS, a subject of the King of Austria, and a resident of Canton, in the county of Stark and State of Ohio, have invented new and useful Improvements in Car-Door Locks, of which the following is a specification.

My invention is an improvement in car door locks, and has for its object to provide 10 a device of the character specified, especially adapted for locking the doors of railroad cars, wherein a locking bar or bolt is provided pivoted at one end to the door, and adapted to engage at the other a hasp or 15 staple on the door, the bar or bolt having a lost motion connection with the door, and wherein a guide is provided for the bolt.

In the drawings:

Figure 1 is a side view of a box car provided with the improved lock; and

Fig. 2 is a perspective view of the lock.

The present embodiment of the invention is shown in connection with the sliding door 1 of a box car 2, and the lock comprises a bolt 3, having at one end a slot 4 and at the other a head 5 closely resembling the head of a hammer, and adapted to engage with the poll or square end of the head is a species 25 of socket 6 secured to the door casing of the car. This head has a transverse opening 7, which is adapted to register with a similar opening in the socket to receive a seal indicated at 8. The slot 4 of the bolt is engaged by a headed pin 9 secured to the car door, 30 and the pin has a spacing bushing or arbor 10 between the bolt and the car, to properly space the bolt from the car.

The bolt is provided with a handle 11 for convenience in operating the same, the said 40 handle being in the form of a pin having a wheel or disk at its outer end for engagement by the hand of the operator, and the pin moves within the slot 12 of an arc shaped guide 13. This guide has its ends 45 offset in the same direction as shown at 14 and secured to the door, and the pin moves in the guide, while the bolt moves between the guide and the car door. The connec-

tions, indicated at 15, between the offset portions 14 and the body of the guide serve as 50 stops for limiting the movement of the bolt in each direction, the bolt engaging and resting upon these portions at the end of its movement to opening or closing position.

In use, when it is desired to open the car, 55 the bolt is swung to the opposite end of the guide, by grasping the handle 11. To lock the car, the door is closed and the bolt is swung until the head 5 will engage the socket. Should it be impossible to entirely 60 close the door, the slot connection between the bolt and the door permits the engagement to take place without the complete closing of the door.

I claim:

1. A lock for car doors comprising a bolt having at one end a longitudinally extending slot and at the other a transverse head, a socket adapted for connection with the car for engagement by the head, said head and 70 socket having registering openings for receiving a seal, a headed pin on the door engaging the slot and having a spacing bushing between the bolt and the car, an arc shaped guide having its ends offset and secured to the door, the bolt moving between the guide and the car and engaging in open and closed positions the ends of the guide, said guide having a slot extending approximately the full length thereof, and the bolt 75 having a handle extending through the slot.

2. A lock for car doors comprising a bolt having at one end a longitudinally extending slot and at the other a transverse head, a socket adapted for connection with the 85 car for engagement by the head, said head and socket having registering openings for receiving a seal, a headed pin on the door engaging the slot and having a spacing bushing between the bolt and the car, an arc 90 shaped guide having its ends offset and secured to the door, the bolt moving between the guide and the car and engaging in open and closed positions the ends of the guide.

3. A lock for car doors comprising a bolt 95 having at one end a longitudinally extend-

ing slot and at the other a transverse head, a socket adapted for connection with the car for engagement by the head, a headed pin on the door engaging the slot and having a spacing bushing between the bolt and the car, an arc shaped guide having its ends offset and secured to the door, the bolt moving between the guide and the car and engaging

in open and closed positions the ends of the 10 guide.
